UNITED STATES PATENT OFFICE.

GEORGE H. REIMER, OF FULTON, ILLINOIS, ASSIGNOR TO PATENT NOVELTY COMPANY,
OF FULTON, ILLINOIS, A CORPORATION OF ILLINOIS.

TOWEL-HOLDER.

1,235,600.

Specification of Letters Patent.

Patented Aug. 7, 1917.

Application filed September 2, 1916. Serial No. 118,287.

To all whom it may concern:

Be it known that I, GEORGE H. REIMER, a citizen of the United States of America, and resident of Fulton, Whiteside county, Illinois, have invented a certain new and useful Improvement in Towel-Holders, of which the following is a specification.

My invention relates to towel holders of that kind in which a towel is removably held 10 in place between a ball and a stationary portion of the structure, the ball being arranged to gravitate along an incline by which it is forced against said portion, whereby upward movement of the ball from clamping position will release the towel.

Generally stated, the object of my invention is to provide an improved construction and arrangement whereby the entire towel holder, with the exception of said ball, may 20 be constructed from sheet-metal, and whereby the said incline is formed in the bracket-plate of the structure, so that the towel is held between the ball and a depending arm which is spaced a distance from the bracket- 25 plate and rigidly secured thereto at its upper end, as will hereinafter more fully appear.

To this and other useful ends, my invention consists in matters hereinafter set forth 30 and claimed.

In the accompanying drawings, Figure 1 is a front elevation of a sheet-metal towel holder embodying the principles of my invention.

Fig. 2 is a vertical section on line 2—2 in Fig. 1.

Fig. 3 is a transverse section on line 3—3 in Fig. 1.

Fig. 4 is a front elevation of a portion of 40 the bracket-plate, showing the groove in which the ball is movable up and down.

Fig. 5 is a rear elevation of the said towel holder, showing the upper portion thereof broken away for convenience of illustration.

As thus illustrated, my invention comprises a bracket-plate A provided with a rim a, whereby said bracket-plate has a chamber 1 at the back or rear side thereof. The upper and lower ends of said bracket- 50 plate may be adapted in any suitable manner to be attached to a vertical wall-surface. The lower portion of said bracket-plate is formed with a bead or ridge 2 which stands out from the front surface of the bracket-plate, and a vertically disposed groove 3 is surrounded by this bead, said groove being

of maximum depth at its upper end and of minimum depth at its lower end, whereby said groove tapers downward and becomes gradually shallower toward its lower end. 60 The upper end-portion of said groove is of about the same depth as the chamber 1, whereby the bulge 4 formed by this groove on the back of the bracket-plate will about touch the wall when the plate is secured in 65 place. In this way, the rim a not only stiffens the bracket-plate to give it the requisite rigidity, but serves also to provide the chamber 1 into which the bulge 4 may extend in order to give the groove 3 the necessary or desired depth. The bead 2 is provided with an upper horizontal slot 5, and also with vertical slots 6 at each side of the groove 3, in the manner shown more clearly in Figs. 4 and 5. This bead 2, and also the 70 groove 3, stiffen the bracket-plate A, so that it is quite rigid, but the resiliency of the sheet-metal is, of course, retained to some extent.

The ball B is of a size to travel up and 80 down in the groove 3, and is retained in position by the arm C which is made of sheet-metal and provided with lugs c which are inserted through the slots 5 and 6 and bent over upon the rear surface of the bracket-plate, as shown in Fig. 5. The arm C is, it 85 will be seen, formed on its front surface with a marginal bead 7, so that the front surface of said arm is provided with a channel 8, said bead and channel disappearing at the 90 upper end of the head portion of said arm. This head portion is formed by vertical side-walls 9 which extend downward as far as the lower ends of the slots 6, and which combine with the curved upper-portion 10 of the 95 front wall to provide the hollow head by which the arm C is rigidly secured to the bracket-plate. The depth of the channel or groove 8 is such, it will be seen, that the inner surface of the arm C, between the side 100 portions of the bead 7, is not in line with the inner edges 11 of the arm, this inner surface 12 of the arm being slightly in rear of the vertical plane of said edges, whereby the towel can be easily inserted between said 105 arm and the ball B, as indicated in dotted lines in Fig. 2.

After the towel is inserted, as indicated, it can then be released by raising the ball from the position shown in Fig. 2, so that 110 the ball will recede from the arm C, thus permitting the towel to be withdrawn. The

ball then gravitates to its lowest position, and to again insert the towel it is simply necessary to lift it upward between the ball and the arm C, and to then let go, the weight 5 of the ball causing it to instantly move downward and press the towel against the arm. This, it will be seen, is because of the fact that the groove 3 tapers downwardly, and becomes more shallow toward its lower 10 end, thus causing the ball to gradually move outward against the arm C as it gravitates downward in the groove. The bulge 11 on the inner side of the arm C, formed by the groove 8 in the sheet-metal, provides a 15 rounded surface against which the towel is clamped by the ball, and whereby the insertion and removal of the towel is facilitated.

From the foregoing, it will be seen that 20 the holder comprises front and rear stiff jaws of sheet-metal, the rear jaw being formed by a stiffened section of the sheet-metal of the bracket-plate A, and the line of distortion of the metal leaving a flat area immediately outside thereof. Thus, the ball B travels in the groove of one jaw and directly engages the sheet-metal of the other jaw, so that the towel is positively clamped between the ball and the sheet-metal.

30 The bracket plate which provides the rear jaw, it will be seen, has the sheet-metal thereof so distorted that it prevents buckling of the bracket plate when the ball is forced downward between the two jaws. The front 35 jaw, of course, when the ball is forced downward, becomes a lever, so to speak, with its fulcrum at the upper end thereof, and this powerful lever action would cause a buckling of the bracket plate if the latter were 40 left perfectly flat. With the distortion of the sheet-metal, however, to form a stiffened section which provides the rear jaw, the bracket plate is prevented from buckling at the head of the front jaw when the ball is 45 forced downward.

Thus, the bracket-plate A, which is substantially wider and longer than the front jaw C, has the rear jaw outlined thereon by the bead 2 or other suitable swaging of the 50 metal, so that a considerable area is left outside of the rear jaw, and whereby, as stated, the bracket-plate is prevented from buckling under the powerful leverage exerted by the front jaw.

55 What I claim as my invention is:

1. A towel holder comprising front and rear stiff jaws of sheet-metal, said rear jaw consisting of a sheet-metal bracket-plate provided with a bead which stands out from 60 the front surface thereof, and with a vertically disposed groove surrounded by said bead, which groove tapers downward and becomes shallower toward its lower end, a

ball movable up and down in said groove, and said front jaw consisting of a sheet-metal arm having its upper end rigidly secured to the upper portions of said bead, the depending portion of said arm coöperating with said ball to clamp the towel, and said bracket-plate having its rear side provided 70 with a chamber containing the rearward bulge which is formed in the sheet-metal by said groove, which bracket-plate is thereby adapted to be secured flatwise against a vertical wall-surface. 75

2. The said towel holder (substantially as set forth in claim 1), said arm having a bead extending downward at each side and across the lower end thereof, so that said arm is provided on its outer surface with a groove extending vertically thereof and forming a bulge on the inner surface of the arm to engage the towel. 80

3. The said towel holder (substantially as set forth in claim 1), said arm having its upper end provided with side walls which are secured to the bracket-plate, and said arm having a groove extending up and down thereof to stiffen the arm. 85

4. A towel holder comprising front and rear stiff jaws of sheet-metal, means to rigidly connect together the upper portions of said jaws, so that the two jaws in their entirety are substantially unyieldingly opposed to each other, one jaw having a longitudinal groove which converges downward toward the other jaw, and a ball movable downward by gravity in the groove and thereby adapted to be forced by this jaw directly against the other jaw, said rear jaw consisting of a stiffened section of a sheet-metal bracket plate, which plate is substantially wider and longer than said front jaw, said section being formed by swaging of the sheet-metal adjacent said means and downward therefrom, thereby forming said groove, leaving an area outside of the line of swaging, whereby the rear jaw and its said groove are outlined on the face of the bracket-plate by said line of swaging, and said means comprising a hollow head integral with said front jaw and formed with top and side walls having the edges thereof secured at the upper and lower ends of the head to the rear jaw inside of said outline thereof, to prevent buckling of the bracket-plate by the lever action of the front jaw 100 when the ball is forced downward, and so that the towel may be clamped directly between said ball and a sheet-metal jaw by the pressure of sheet-metal on the other side of the ball. 105

110 Signed by me at Fulton, Illinois, this 24th day of August, 1916.

GEORGE H. REIMER.
